UNITED STATES PATENT OFFICE.

FINLEY R. PORTER, OF NEW YORK, N. Y., ASSIGNOR TO PORTER ENGINE DEVELOPMENT, INC., OF NEW YORK, N. Y., A CORPORATION OF NEW YORK.

INTERNAL-COMBUSTION ENGINE.

Application filed March 13, 1924. Serial No. 699,080.

This invention consists in an internal combustion engine of the rotary valve type in which each cylinder has an axially arranged passage and port for the admission of the motive fluid and escape of the combusted gases, each valve chest has separate inlet and discharge ports and each valve has a single peripheral bridge port located in the same plane as the cylinder and valve chest ports.

10 This invention further consists in the provision of an oil impregnated self lubricating hard material as a sleeve bearing for the valve and also the provision of a packing of oil impregnated self lubricating hard material engaging the side of the valve around the cylinder port.

15 This invention further consists in certain improvements in the construction, form and arrangement of the several parts of the engine as will be hereinafter fully pointed out and claimed.

20 Objects of this invention are:—To ensure more perfect cooling and lubrication of the parts;—more perfect combustion and economy in the use of the motive fluid than heretofore;—greater accessibility of the parts;—reduced wear and less necessity for close fitting of the valve and its bearing;—less liability of leakage of the gases;—and less unbalanced pressure on the valve than heretofore.

25 A practical embodiment of this invention is represented in the accompanying drawings, in which—

30 Fig. 1 represents in vertical longitudinal section so much of an internal combustion engine of the rotary valve type as includes this invention.

35 Fig. 2 represents a detail section taken in the plane of the line II—II of Fig. 1.

40 Fig. 3 represents a detail section taken in the same plane with the valve port in the position to open the cylinder port to the exhaust port.

45 Fig. 4 represents a similar section with the valve port in position to open the motive fluid inlet port to the cylinder port.

50 The engine may be composed of as many cylinders as desired. One cylinder and its valve and adjacent parts will now be described.

55 The cylinder is denoted by 1 and its piston or combustion chamber by 2. The outer end of the cylinder 1 is provided with a reduced neck 3, forming an axially arranged

passage and port 4 of reduced size in communication at its inner end with the cylinder chamber 2 and at its outer end with the side of the rotary valve 5 disposed transversely to the cylinder in the circular bore 6 of a valve chest 7. A removable valve bearing sleeve 8 of oil impregnated self lubricating hard material, such as an oil absorbing metal, is interposed between the side of valve 5 and the walls of the bore 6 so that the valve bearing needs no additional supply of oil to lubricate it. A motive fluid inlet port 9 and a combusted gas exhaust port 10 both lead through the walls of the valve chest 7 and self lubricating bearing sleeve 8 to the side of the rotary valve 5 in the same plane as the axially arranged cylinder port 4. In the present arrangement, the inlet and exhaust ports 9 and 10 are shown as located diametrically opposite each other and the cylinder port 4 located half way between them.

60 The rotary valve 5 has a peripheral bridge port 11 located in the same plane as the inlet, exhaust and cylinder ports, which valve port is of sufficient length to open communication between the inlet port 9 and the cylinder port 4 when the valve is in one position and to open communication between the cylinder port and the exhaust port 10 when the valve is in another position of its rotary movement.

65 At the outer end of the neck 3 of the cylinder I provide an annular packing chamber 12 opening to the side of the valve 5. Within this annular chamber 12 I locate a ring 13 which has a screw-threaded engagement 14 with the wall of the annular packing chamber 12. A packing is also located within the packing chamber 12, which packing is herein shown as comprising a shell 15 and a removable insert element 16 composed of an oil impregnated self lubricating hard material, preferably metal. The outer end of this insert element 16 engages the wall of the rotary valve 5 around the cylinder port 4. Resilient means are employed for holding the oil impregnated self lubricating element 16 in engagement with the side of the valve, which means in the present instance comprises a compound diaphragm located within the packing chamber 12. The edge of the outer wall 17 of the compound diaphragm is engaged with the back of the packing shell 15, said edge being preferably permanently

joined to the packing shell as, for instance, by welding. The inner wall 18 of the compound diaphragm has its edge clamped between the inner end of the ring 13 and the 5 bottom of the annular chamber 12, a soft metal washer 19 being preferably interposed between the said edge of the diaphragm and the bottom of the annular chamber. Gas tight joints are thus produced at these 10 points.

From the above description it will be seen that the insert element 16 may be removed and replaced when so desired and that the packing as a whole may be removed 15 and replaced as desired.

The spark plug 20 is so located that its inner end projects into the cylinder port 4.

The water jacket 21 for the cylinder and valve chest provides a considerable cooling 20 space 22 around the cylinder port 4 where it is most needed.

In operation:—

Presupposing the valve to be in the position of its rotary movement disclosed in 25 Figs. 1 and 2, the further rotary movement of the valve to the position shown in Fig. 3 will bring the cylinder port 4 into open communication with the exhaust port 10 to permit the discharge of the combusted gases 30 from the cylinder chamber 2. The further rotary movement of the valve 5 to the position shown in Fig. 4 will bring the motive fluid inlet port 9 into open communication with the cylinder port 4, the incoming 35 charge of motive fluid driving the combusted gases which remained in the valve port 11 into the cylinder chamber.

It will be observed that the entire valve 40 mechanism is made self lubricating by the provision of the valve bearing sleeve in the valve chest and by the provision of the packing element, both of oil impregnated self 45 lubricating hard material, such as an oil absorbent metal. It will be noted that the bearing sleeve and the packing element may be removed at pleasure and replaced, or re-impregnated.

It will also be noted that a close fit is not 50 required between the rotary valve and its bearing sleeve as the packing which surrounds the cylinder port and engages the side of the valve serves to prevent leakage at this vital point. This feature allows the 55 rotary valve to be so loosely fitted as to prevent all liability of the binding of the valve because of distortion, due to heat or other factors. Also it will be noted that the pressure of the packing against the side 60 of the valve serves to hold the valve against the opposite side of its bearing sleeve and thus prevents the valve from knocking. Furthermore the valve is subjected to the 65 minimum heat and wear because the heat and pressure on the valve is confined within the packing which surrounds the cylinder

port, while the bearing surface for the valve available to resist this pressure is very extended, making the unit pressure per inch very low.

It will also be noted that because of the 70 construction of the parts the incoming charge of motive fluid materially helps to absorb the heat given off by the heated exhaust gases.

One great advantage in the use of the 75 single rotary valve is that it permits of a small tubular cylinder passage which ensures great turbulence to the incoming charge of motive fluid in the cylinder chamber, which turbulence produces a very dry 80 mixture and allows of much higher compression being carried.

A further aid to the resultant economy due to the high pressure is the single port in the rotary valve which, at the end of the 85 exhaust stroke, remains full of the burnt gases which at the beginning of the induction stroke are swept into the cylinder chamber, thereby increasing by a considerable extent 90 the burnt gases retained therein. It is obvious, however, that at the time of inlet closing the cylinder passage will be full of compressed motive fluid of the proper mixture to ignite easily, since this portion of the motive fluid charge is unaffected by the 95 turbulence on the compression stroke due however, to the fact that the volume of motive fluid contained in said cylinder passage must, of necessity, due to the shape of this 100 passage, expand the greater part of its volume inwardly into the cylinder chamber proper, thereby producing a very violent turbulence and causing a very complete burning of the motive fluid charge in the cylinder chamber regardless of the proportion of 105 air and fuel in the mixture, within very wide limits.

The greatest benefit from the excessive amount of burnt gases contained in the cylinder chamber is to be had under throttle 110 conditions, since the amount of burnt gases remaining in the cylinder is a constant factor, and as the motive fluid charges vary with the throttle opening, the compression pressures would not vary in a constant ratio 115 with the amount of motive fluid admitted. For instance assuming that the average internal combustion engine as applied to a road vehicle operates under a quarter throttle or less a greater portion of the time, 120 the economy to be realized would be considerable.

Any suitable oil impregnated self lubricating hard material may be used for the bearing sleeve 8 and the packing element 16, 125 such, for instance, as "genalite" made by the General Electric Company of Schenectady, New York, genalite being a molded porous material comprising synthetic bronze and graphite so combined that the material will 130

absorb by capillary attraction from 2% to 3% by weight of lubricating oil.

It is evident that various changes may be resorted to in the construction, form and arrangement of the several parts without departing from the spirit and scope of my invention; hence I do not wish to be limited to the particular embodiment herein shown and described, but—

10. What I claim is:—

1. In an internal combustion engine, a cylinder, a rotary valve, a packing therefor, and a compound diaphragm having substantially parallel walls, the unjoined edges of said walls having gas tight joints with the packing and cylinder respectively, said compound diaphragm acting as a resilient means for holding the packing in engagement with the valve.
20. In an internal combustion engine, a cylinder, a rotary valve, a packing therefor, and a compound diaphragm having outwardly extended substantially parallel walls, the outer unjoined edges of said walls having gas tight joints with the packing and cylinder respectively, said compound diaphragm acting as a resilient means for holding the packing in engagement with the valve.
25. In an internal combustion engine, a cylinder, a rotary valve, a packing therefor, and a compound diaphragm having substantially parallel walls, the edges of said walls having gas tight joints with the valve, said compound diaphragm having outwardly extended substantially parallel walls, the outer edges of said walls having gas tight joints with the packing and cylinder respectively.

3. In an internal combustion engine, a cylinder having a port and a packing chamber surrounding said port, a rotary valve having a port, a packing located in said chamber and surrounding said cylinder port, and a compound diaphragm located in said packing chamber and acting as a resilient means for holding the packing in engagement with the valve, said compound diaphragm having substantially parallel walls, the edges of said walls having gas tight joints with the packing and cylinder respectively.

4. In an internal combustion engine, a cylinder having a port and a packing chamber surrounding said port, a rotary valve having a port, a packing located in said chamber and surrounding said cylinder port, and a compound diaphragm located in said packing chamber and acting as a resilient means for holding the packing in engagement with the valve, said compound diaphragm having outwardly extended substantially parallel walls, the outer edges of said walls having gas tight joints with the packing and cylinder respectively.

In testimony, that I claim the foregoing as my invention, I have signed my name this fifth day of March, 1924.

FINLEY R. PORTER.
